UNITED STATES PATENT OFFICE.

CHAUNCEY COOK CLARK, OF PHILADELPHIA, PENNSYLVANIA, ASSIGNOR OF ONE-HALF TO JAMES G. CARSON, OF PHILADELPHIA, PENNSYLVANIA.

WATER-PURIFIER.

SPECIFICATION forming part of Letters Patent No. 703,541, dated July 1, 1902.

Application filed January 22, 1901. Serial No. 44,274. (No model.)

To all whom it may concern:

Be it known that I, CHAUNCEY COOK CLARK, a citizen of the United States, residing at Philadelphia, in the county of Philadelphia and State of Pennsylvania, have invented certain new and useful Improvements in Liquid-Purifiers; and I do hereby declare the following to be a full, clear, and exact description of the invention, such as will enable others skilled in the art to which it appertains to make and use the same.

My invention relates to purifier mechanism for the purpose of the removal of all of the impurities and foreign substances carried by or held in suspension by the liquid to be effected, the deposit of such impurities within a closed receptacle, and the employment of means for their withdrawal therefrom, together with means to remove from the surface of the liquid any floating matter of too light a character to be deposited, also means to withdraw the pure liquid below its upper surface, its cooling while the mechanism is in operation for certain purposes, and its heating for other purposes, the introduction of electric current to attack the inflowing fluid for the purpose of its purification, safety appliances to prevent damage from hydrostatic pressure, if at any time there is an unintended stoppage of the apparatus, which is continuous and automatic, and special mechanisms for the purposes enumerated and which will be further pointed out in the specification, and illustrated in the accompanying drawings, in which—

Figure 1 is a central vertical section as to the principal parts. Fig. 2 is a cross-section on line $x-x$, Fig. 1. Fig. 3 is an enlarged section of the inlet-chamber. Fig. 4 is a plan view of the electrodes. Fig. 5 is an enlarged section of the induction stuffing-boxes.

Similar figures of reference indicate similar parts throughout the views.

Referring to Fig. 1, it will be seen that a cylinder 1 is employed to make a close and tight receptacle, into the ends of which are secured circular heads having outer cylindrical rings 2 3, which enter cylinder 1, inner plates 4 5, which form tube-sheets, with stiffening-ribs 6 7 8 9. Removable covers 10 11, with ribs 12 13 14 15, are secured to the heads,

forming circulating-chambers 16 17, having openings 18 19, to which may be attached the necessary pipes to convey cooling water or steam into or out of chambers 16 17, using the ones most convenient for the purpose. Tubes 20 extend from tube-sheet 4 to tube-sheet 5, their ends being secured in expansion stuffing-boxes of any of the well-known and suitable constructions in use for similar purpose, and therethrough and through tubes 20 the chambers 16 17 are put in communication for the constant passing of cold water or steam to keep the liquid within cylinder 1 at a proper temperature for the purposes of the apparatus, the tubes not being in use when fresh-water purification is in progress; but for salt water and other liquids (other than fresh water) a current of cold water enters chamber 16, goes through tubes 20, and discharges at 19 to overcome the heat generated by the electric action on the great amount of mineral substances. When used as a feed-water heater and purifier, steam is passed through tubes 20, generally exhaust steam. A trap drain-pipe 21 connects to the bottom of chamber 16, and valve 22 opens and closes the pipe and is only used to take away the water of condensation when the apparatus is using steam.

An inlet-chamber 23 is inserted through cylinder 1 near chamber 16. It is secured to the cylinder 1 and has a cover 24 secured thereto. Mounted above the cover is a T-pipe 25, in which is inserted inlet-pipe 26 for the inflowing of the liquid to be treated, and above the T-pipe is located a suitable relief-valve 27, having means to relieve any excess of pressure above a fixed limit.

Within inlet-chamber 23 is an insulated lining 28, and suspended within the lining is a series of electrodes, 29 being positive and 30 being negative, and their mode of suspension is best seen in Fig. 3. The electrodes will usually be of copper; but where great durability is required they may be plated with platinum, and where only coloring-matter is to be removed or partial purification is required iron may be used, as it answers every purpose and is very economical. They have multiple perforations 31, through which the incoming liquid must pass and where it is

electrolyzed, the heavier decomposed substances and matter held in suspension falling by gravity to the bottom of cylinder 1 and the lighter ones rising to dome 47. The electrodes 29 30 are connected to any suitable system of electrical generation, the current being conveyed by conductors 32 33, having insulations 35, and nut 36 screwed on conductors 32 33, which are screw-threaded for the purpose.

At the sides of cover 24 are insulated stuffing-boxes 37, (best seen in Fig. 5,) they being provided with follower-caps 38, compressing insulating-packing 39 to prevent the outflow of liquids, an insulation 40 being provided for part 38 and an insulation 41 for part 37. A tube 42 delivers the electrolyzed liquid to the interior of cylinder 1, where the released impurities descend to the bottom and can at any desirable time be drawn off through pipes 43, controlled by valves 44 and connected to discharge-pipe 45, so that one or more of pipes 43 and valves 44 may be used, and when a thorough cleaning is necessary wash-out plugs 46 may be removed, giving access for the introduction of hose or other means. Near chamber 17, at the opposite end of cylinder 1 from inlet-chamber 23, is placed a dome 47, in which the light floating impurities are gathered and where they may be drawn off by pipe 48, controlled by valve 49, while delivery-pipe 50, secured to flange 51, descends below the dome and into the cylinder to the body of pure liquid and, joining pipe 52, affords an outlet therefor. The action of the apparatus is continuous during the supply of liquid and the electric current and is automatic when once set in operation, as the electrical current will flow in sufficient volume to attack the impurities as presented, a heavy current for many impurities and a lighter current as purification progresses or the liquid is more nearly pure.

I claim—

1. In a liquid-purifier a horizontal cylindrical and inclosing receptacle, a vertical cylindrical inlet-chamber inserted within the receptacle, a series of perforated disk electrodes inserted therein, heads forming in closed chambers at the ends of the receptacle, inlet and outlet passages to and from the chambers, and tubes extending from chamber to chamber through the receptacle.

2. In a liquid-purifier, a closed receptacle, chambers therefor at each end, tubes from chamber to chamber through the receptacle, an inlet-chamber inserted in the receptacle, an insulated lining for the chamber, and a series of perforated intercepting-electrodes fixed therein.

3. In a liquid-purifier, a closed receptacle, a vertical cylindrical insulated inlet-chamber partly within and partly without the receptacle, a series of perforated disk electrodes arranged across and within the chamber, insulated and liquid-retaining stuffing-boxes for the inlet-chamber, and means therethrough

for positive and negative electric connection to alternate electrodes.

4. In a liquid purifier, a closed receptacle, an inlet-chamber projecting from the exterior to the interior of the receptacle, an insulating-lining for the chamber, a series of electrodes in the chamber, means for electric connection from the exterior of the receptacle and the inlet-chamber, to the electrodes, through stuffing-boxes, followers for the stuffing-boxes, insulation for the stuffing-boxes and the followers, and liquid-retaining packing within the stuffing-boxes.

5. In a liquid-purifier, a receptacle, a chamber inserted into the receptacle from its exterior, and means thereto connected for conveying liquid, a series of perforated electrodes in the chamber, a closed bottom for the chamber, a delivery-pipe leading therefrom toward the bottom of the receptacle, a chamber at each end of the receptacle, inlets and outlets for the chambers, and a series of tubes connecting the end chambers, through the receptacle, and passing the sides and bottom of the inserted chamber.

6. In a liquid-purifier, a closed cylindrical receptacle, an inlet-chamber mounted upon one end of and entering the receptacle, an inlet thereto, a series of electrodes therein, electrical conductors thereto from a source of electrical energy exterior to the receptacle, a passage to pass the products of decomposition from the inlet-chamber to the bottom of the receptacle, a dome mounted on the end of the receptacle opposite the inlet-chamber, wherein the lighter impurities may arise above the purified liquid, and a pipe and valve for their withdrawal.

7. In a liquid-purifier, a closed horizontal cylindrical receptacle, a chamber supported upon and entering the receptacle near one end, an inlet thereto, a series of electrodes in the chamber, conductors from the electrodes to a source of electrical energy exterior to the receptacle, a passage from the chamber to the bottom of the receptacle, a dome located at the top of the receptacle at the opposite end from the chamber, for collecting the lighter impurities, and means to withdraw these impurities from the receptacle, through its dome, and at a point above the body of purified liquid in the receptacle.

8. In a liquid-purifier, an inclosing horizontal cylindrical receptacle, a chamber inserted within the receptacle near one end, a series of electrodes within the chamber, electrical conductors for the electrodes, a passage leading from the chamber toward the bottom of the receptacle, a dome near one end of the receptacle, and above the receptacle, and means entering the dome whereby to withdraw the purified liquid below the impurities arising within the dome.

9. In a liquid-purifier, an inclosing horizontal cylindrical receptacle, a cylindrical inlet-chamber inserted therein through the top, near one end, a series of perforated disk elec-

trodes therein, electrical conductors therefor leading out of the receptacle and the chamber, a pipe extending from the chamber to the receptacle at its lower part, and a series of pipes and valves for the withdrawal of the products of decomposition from within the receptacle, at its lower part.

10. In a mechanism of the character described, a horizontal cylindrical fluid-receptacle, an inserted inlet-chamber, a series of electrodes therein, adapted to intercept the inflow, chambers at the ends of the recep-

tacle, inlets and outlets for the chambers, a series of tubes from chamber to chamber through the receptacle, and from one of the 15 chambers means to withdraw the products of condensation.

In testimony whereof I affix my signature in presence of two witnesses.

CHAUNCEY COOK CLARK.
